TOWEL RING

LaVerne E. Clayton, Rockford, Ill., assignor to Amerock Corporation, Rockford, Ill.

Filed May 25, 1970, Ser. No. 32,118

Term of patent 14 years

Int. Cl. D6—99

U.S. Cl. D33—32

FIG. 1 is a top view of a towel ring incorporating my new design.

FIG. 2 is a front view of the towel ring.

FIG. 3 is a side view as seen from the left in FIG. 2.

FIG. 4 is an enlarged sectional view taken along the line 4—4 in FIG. 2.

FIG. 5 is an enlarged sectional view taken along the line 5—5 in FIG. 2.

FIG. 6 is a fragmentary sectional view taken along the line 6—6 in FIG. 3.

I claim:

The ornamental design for a towel ring, as shown and described.
